Attorney

UNITED STATES PATENT OFFICE.

BENJAMIN WOLHAUPTER, OF NEW ROCHELLE, NEW YORK, ASSIGNOR TO THE RAIL JOINT COMPANY, OF NEW YORK, N. Y., A CORPORATION OF NEW YORK.

TRACK LINER.

Original application filed December 26, 1923, Serial No. 682,769. Divided and this application filed April 17, 1925. Serial No. 23,887.

To all whom it may concern:

Be it known that I, BENJAMIN WOLHAUPTER, a citizen of the United States, residing at 28 Neptune Ave., New Rochelle, in the county of Westchester and State of New York, have invented certain new and useful Improvements in Track Liners, of which the following is a specification.

This invention relates to track liners adapted for use in relining railroad tracks, and has particular reference to a track liner of the general type shown in my copending application, Serial Number 682,769, filed December 26, 1923, which has resulted in Patent No. 1,538,775, of May 19, 1925, of which the present case is a division.

A primary object of the invention is to provide an efficient track liner plate of simple and comparatively light construction which affords ample anchorage or footing in the ballast and provides a series of fulcrum points for the crow-bar or other lever. Also it is the purpose of the invention to provide a track liner plate by means of which the track may readily be shifted laterally in successive steps with a minimum physical effort, this being particularly advantageous when a heavy or tight track is being operated upon, or whenever a small number of men are employed at a particular point along the track.

A special object of the invention is to provide a form of construction which affords the trackman a new fulcrum point on each slight advance of the rail, thereby providing maximum efficiency and flexibility of application.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings, in which:

Figure 1 is a view illustrating the application of the invention.

Figure 2 is a top plan view of the track liner plate shown in side elevation in Figure 1.

Similar reference characters designate cor-

responding parts throughout the several figures of the drawings.

In practice the plate or base B may be made of malleable iron or pressed steel, and because of its relatively shallow depth it may be readily placed in position over the ballast and beneath a rail, thereby to provide the desired base or footing for the toe T of the fulcruming lever L which may be a crow-bar or other similar member capable of being manipulated to exert the desired shifting or fulcruming pressure on the base flange 7 of the rail R.

Referring more particularly to the plate B it will be observed that the same is provided with two longitudinal series 8 and 9 of transverse fulcruming shoulders 10 and 11, respectively. As the plate is formed of pressed steel or malleable iron the underside thereof preferably assumes the same stepped or shouldered formation as the upper side, thereby providing a plurality of angular corrugations 12 in the plate which are present at the bottom face thereof the ballast engaging anchoring shoulders 13. As shown, the corrugations of one of the series 8, are disposed in staggered relation to the corrugations of the series 9, thus staggering the fulcruming shoulders 10 and 11 as well as the anchoring shoulders 13, thus providing a multiplicity of ballast engaging shoulders at the bottom of the plate, and likewise a multiplicity of lever engaging shoulders at the top of the plate.

The plate is reversible so that it becomes immaterial, in operation, which side is uppermost. In using the plate it will be readily apparent that the crow-bar or other lever is successively fulcrumed on the shoulders 10 and 11 until the track has been shifted the required distance. If the track is to be moved a relatively long distance either set of shoulders may be used consecutively, or shoulders of opposite rows may be used alternately thereby obtaining a finer adjustment of the fulcrum point and consequently effecting a lesser movement of the rail with a correspondingly less effort in the manipulation of the lever 6.

From the foregoing, it will be apparent that the present invention makes adequate provision for a reversible fulcruming plate having a plurality of staggered abutment

shoulders on both sides thereof, thereby materially increasing the range of use of the invention, as will be readily understood to those skilled in the art.

5 Without further description, it is thought that the features of the invention will be readily apparent, and it will of course be understood that changes in the form, proportion and minor details of construction 10 may be resorted to, without departing from the spirit of the invention and scope of the appended claims.

I claim:

1. A corrugated fulcrum plate for track liners, the corrugations forming fulcrum shoulders on one side of the plate and anchoring shoulders on the other side of the plate, the said corrugations on both sides of the plate being in staggered formation.

20 2. A reversible corrugated fulcrum plate for track liners, the corrugations forming fulcrum shoulders on one side of the plate and anchoring shoulders on the other side of the plate, the said corrugations on both 25 sides of the plate being in staggered formation.

3. A corrugated fulcrum plate for track liners, the corrugations forming on the up-

per side of the plate a pair of longitudinally disposed series of fulcrum shoulders, the shoulders of one series being staggered relative to the shoulders of the other series, the corrugations forming on the under side of the plate a plurality of anchoring shoulders.

4. A reversible track liner plate having on its upper and lower sides respectively a pair of longitudinally disposed series of fulcrum shoulders and a pair of longitudinally disposed series of anchoring shoulders, the shoulders of one series being staggered relative to the shoulders of the other series.

5. A reversible corrugated track liner plate, the corrugations extending transversely of the plate and arranged in a pair of longitudinally disposed series and forming on opposite sides of the plate fulcrum and anchoring shoulders, the shoulders of one series being staggered relative to the shoulders of the other series.

In testimony whereof I hereunto affix my signature in the presence of two witnesses.

BENJAMIN WOLHAUPTER.
